United States Patent Office

Des. 185,359
Patented June 2, 1959

185,359

HEADLIGHT FOR INDUSTRIAL EQUIPMENT OR THE LIKE

William P. Gross, Arlington Heights, Ill., assignor to
Goodman Manufacturing Company, Chicago, Ill., a
corporation of Illinois

Application September 26, 1957, Serial No. 47,883

Term of patent 14 years

(Cl. D48—32)

Figure 1 is a front perspective view of a headlight for industrial equipment or the like, illustrating the new design;

Figure 2 is a side elevational view thereof;

Figure 3 is a front elevational view thereof;

Figure 4 is a top plan view thereof;

Figure 5 is a bottom view thereof; and

Figure 6 is a rear view thereof.

I claim:

The ornamental design for a headlight for industrial equipment or the like, substantially as shown.
